MOLD MAKING MACHINE

Earl F. Oyster, Shaker Heights, Ohio, assignor
to The Osborn Manufacturing Company, Cleve-
land, Ohio, a corporation of Ohio

Application October 6, 1930. Serial No. 486,597

5 Claims. (Cl. 121—38)

This invention relates to mold making machines and more particularly to a means for controlling the squeeze and draw operations of such machines. It has among its objects the provision of a control means which will automatically regulate the speed of the draw stroke at its various stages so as to provide the most efficient operation, giving slow or quick movements or cushioning effects at the various stages of the stroke, as may be most appropriate. This invention is particularly applicable to the machine shown in Patent No. 1,781,126, Mechanism for making molds, issued to Earl F. Oyster and Francis N. Gilliland on November 11, 1930.

Other objects and purposes of the invention will be apparent as the description proceeds. A preferred form embodying the principles of this invention is set forth in the following specifications taken in conjunction with the accompanying drawings, although it will be understood that I do not limit myself to this particular form of mechanism.

In the drawings Fig. 1 is a vertical central transverse section on the line 1—1 of Fig. 2; Fig. 2 is a diagrammatic plan view showing the position of the control with relation to the other parts of the mechanism; Figs. 3, 4, 5 and 6 illustrate the control means in various positions.

Referring now particularly to Figs. 1 and 2, a molding machine is illustrated in somewhat conventional style, including a jolt table 10 having the usual guide rods 11 at the four corners and having the valve pin 12, which is a principal element of the control means to which this invention pertains, located at the rear and protected by the jolt table.

In the particular type of machine illustrated in Fig. 1 both the squeezing and drawing are accomplished by the same piston. For convenience this will be termed the draw piston, and is indicated by the reference character 13. A jolt piston 14 of usual construction and forming no part of the present invention is carried within the draw piston. The draw piston 13 is mounted within a casing 15, which provides a cylinder within which the piston 13 moves.

A sleeve 16 closes the top of the cylinder 15 and projects down therein as at 17. The piston 13 is enlarged at its lower end as at 18, this enlarged portion being free to travel upward in the annular space 19, which space is limited at the top by the downward extension 17 of the sleeve 16. The jolt piston 14, secured to the upper end of the jolt piston 14, rests, when not jolting, on the upper end of piston 13 so as to move there-

with, and the pin 12 is in turn fast to the jolt table. Thus the movements of the pin 12 coincide during all squeeze and draw operations with those of the draw piston 13.

The pin 12 extends downward through a valve 69 housing 21, a convenient construction being to have the housing suitably secured at its top to the sleeve 16, as shown.

The pin 12, preferably an integral rod, may conveniently take the form of a straight cylindrical 65 portion 22 for about the upper three-fourths of its length, from which depends a relatively short reduced cylindrical neck 23 below which the pin again gradually tapers outwardly as at 24 resuming its full diameter and cylindrical form for a 70 short distance at the bottom end as indicated at 25. The housing 21 throughout its upper portion fits the full portion 22 of the pin closely throughout its upper length. A small annular lubricant chamber 26 may be provided near the top. Near 75 the bottom of this close fitting portion an air line 27, exhausting from the draw cylinder as shown at 33, is connected into a chamber 28 disposed near the bottom of the upper portion across the direction of travel of the stem 12, the bottom of 80 the chamber 28 being formed by a web 28^A, a port 28^B in which fits the valve stem closely so that when any full section of the valve stem, as 22 or 25, is in the web aperture the flow of air will be shut off.

The lower portion 29 of the valve housing 21 is enlarged to form an air chamber 30 which is conveniently closed by a bottom plug 31. An exhaust line 32 to the atmosphere is connected to the chamber 30, preferably near its upper end. 90 The air line 27, previously mentioned, leads from beneath the head 18 of the draw piston 13 through a passage 33 in the base of the casing 15 to the chamber 28. Thus the exhaust path from the draw cylinder to the atmosphere is through 95 the elements 33, 27, 28, 28^B, 30 and 32, and exhaust is possible only when the portions 23 or 24 of the pin 12 is in the part 28^B. Air to raise the draw cylinder 18 is supplied through a pipe such as 18^A, of greater capacity than the exhaust line, 100 for a reason described below. This line is connected to the cylinder at 18^B.

The operation of the apparatus is apparent by a comparison of the positions of pin 12 shown in Figs. 1, 3, 4, 5 and 6.

Inasmuch as the invention is chiefly operative as an exhaust valve the sequence of operations may be most conveniently considered in the order of Figs. 3, 4, 5, 6 and 1.

In Fig. 3 the parts are shown in the squeezing 110

position, the piston 13 having been moved to the upper limit of its travel by means of air pressure which has been admitted by any convenient inlet (not shown) beneath the head 18. This travel 5 has carried the pin 12 upward so that its bottom portion 25 stands above the chamber 28 thus allowing the air beneath the squeeze cylinder to exhaust through the passage 33, line 27 and chamber 28 into the chamber 30 and thence 10 through the passage 32 into the atmosphere. The rate of the supply of air to hold the squeeze cylinder up is greater than the rate of exhaust, so that the action just described will not be effective to allow the draw piston to fall until the 15 operator cuts off the air supply. Upon cutting off the air supply the release of pressure through the path just described allows a quick drop of the squeeze piston of an inch or two to the position of Fig. 4. The utility of this quick short 20 drop is to remove the mold quickly from the pressure head, and will be understood by reference to Figs. 1 and 2 of Patent No. 1,781,126. Supposing the mold of that patent to be in the 25 squeeze position, up against the pressure head 44, the jacket 43 will partly surround the pressure head. It is advantageous to have it clear quickly, so that the head 44 can be run back and the operator can turn his attention to removal of the jacket after the draw. This quick drop 30 permits the operator's movements to be more efficient.

In Fig. 4 the bottom full diameter portion 25 of the pin 12 cuts off communication between the chambers 28 and 30, thus checking the 35 descent of the piston 13 in the early part of the draw. The length of the portion 25 is so related to the thickness of the web 28^A that the descent is not stopped but only checked, because the momentum of the parts carries the valve section 40 25 below the web 28^A so that escape of air is again allowed past the tapered portion 24. As the descent continues the narrowing of the taper allows faster escape of air, as will be apparent from Fig. 5, with consequent increase of speed 45 of the descent. The speed of the draw becomes greatest when the neck 23 is within the aperture of the web 28^A, but the escape of air is suddenly cut off by the full portion 22 of the pin 12, holding 50 enough air in the draw cylinder to cushion the piston 13 at the bottom of the stroke, thus completing the draw, with the parts in the position shown in Fig. 1.

It will be understood that the foregoing description, relating to a preferred form of the 55 invention, is illustrative and not limiting, and that the scope of the invention is not to be

determined thereby, but by the appended claims.

What I claim is:

1. In a molding machine, in combination, a draw piston adapted for a down drawn movement, an air exhaust line therefor and a valve in 80 said air exhaust line, said valve comprising a port and a closure member therefor adapted for movement by said piston, said closure member comprising means for shutting the exhaust opening of said piston shortly after the beginning of its descending stroke but for a distance less than that through which the piston will be moved by the momentum acquired in such early part of the stroke, means for thereafter progressively increasing the open area of said port, and for finally 85 suddenly closing said port near the bottom of the stroke.

2. In a molding machine, in combination, a draw cylinder, an exhaust air valve operatively connected therewith, said valve comprising a pin 90 movable synchronously with said cylinder, an air passage controlled by said pin, said pin comprising portions adapted to completely close said passage and portions intermediate said first named portions adapted to progressively change the effective area of said passage.

3. In a molding machine, in combination, a draw cylinder, an exhaust air valve for said cylinder, said valve comprising a pin movable by 100 said cylinder and a port adapted to be completely closed by portions of said pin, said pin comprising a short cylindrical bottom portion, an intermediate portion thereabove of diminishing diameter, a further intermediate portion of reduced constant diameter, and a top cylindrical 110 portion, said bottom and top cylindrical portions closely fitting said port.

4. In a molding machine, in combination, a draw piston, a valve pin parallel thereto and movable thereby, an exhaust line below said piston, 115 an air port in said exhaust line, a portion of said pin being adapted to travel through said port a distance equal to the travel of said piston, the upper and lower ends of said portion being adapted to completely close said port and the intermediate elements of said portions being adapted to vary the rate of exhaust at successive positions.

5. In a molding machine, a draw cylinder mechanism including in combination means for allowing sudden exhaust of air beneath said cylinder, means for momentarily checking such exhaust, means for allowing continued exhaust at an increasing rate, means for allowing exhaust at a constant rate, and means for suddenly stopping said exhaust, all in the sequence described. 125 130

EARL F. OYSTER.

CERTIFICATE OF CORRECTION.

Patent No. 1,931,902.

October 24, 1933.

EARL F. OYSTER.

It is hereby certified that error appears in the printed specification of the above numbered patent requiring correction as follows: Page 2, line 79, claim 1, for "drawn" read draw; and that the said Letters Patent should be read with this correction therein that the same may conform to the record of the case in the Patent Office.

Signed and sealed this 12th day of December, A. D. 1933.

F. M. Hopkins

(Seal)

Acting Commissioner of Patents.
